UNITED STATES PATENT OFFICE.

ISAAC W. HEYSINGER, OF PHILADELPHIA, PENNSYLVANIA.

DEVICE FOR HOLDING AND CLAMPING PAPERS, &c.

SPECIFICATION forming part of Letters Patent No. 531,312, dated December 25, 1894.

Application filed October 1, 1894. Serial No. 524,558. (No model.)

To all whom it may concern:

Be it known that I, ISAAC W. HEYSINGER, a citizen of the United States, residing at Philadelphia, in the county of Philadelphia and State of Pennsylvania, have made a certain new and useful Improvement in Devices for Clamping and Holding Papers, &c., of which the following is a full, clear, and exact description, reference being had to the drawings which accompany and form a part of this specification, in which—

Figure 1 is a perspective view of one of my paper holding clamps, one side longitudinally and vertically cut away, to show the working parts beneath, along the dotted line x of Fig. 7, and showing also, in dotted outline other working parts beneath the supporting board, A. Fig. 2 is a longitudinal section showing Fig. 1 with the board depressed upon its spring support, and its clamping jaw raised and tilted up for the reception of papers. Fig. 3 is a perspective view of the working parts, the springs, C C, and the board, A, removed. Fig. 4 is a longitudinal vertical section of my paper holding clamp, in which the position of the clamping jaw is reversed, for holding papers when perforated, and the construction somewhat modified for such purpose. Fig. 5 is a similar view to that shown in Fig. 4 with the board depressed upon its spring support and the clamping jaws open for the reception of papers. Figs. 6, 6^a and 6^b are views in detail of the devices I prefer to use for attachment of my supporting spring or springs to the board, A; and Fig. 7 is a top view, through the board, A, which is shown in dotted outline, of the working parts of my device when modified as described.

The lettering in all the figures is uniform. My invention relates to the construction of devices for clamping and holding papers and the like of the general class shown in United States Letters Patent of G. Bernard Petsche, No. 405,596, and bearing date June 18, 1889, in which a board or other support rests at one end upon a desk or table, or is hung on a nail, and rests against the wall, the other end being raised and supported upon a flexible spring, so that when considerable pressure is applied to the top surface of said board, near its upper or free margin, the spring will yield and the supported end thereof be depressed,

said movement of depression serving to actuate mechanism automatically whereby the clamping jaws are forced open, against spring 55 pressure so as to permit the insertion of loose sheets of paper, and when the pressure is released, the action of said spring, as the free end of the board rises, will again force down the said clamping jaws and grasp and hold 60 said papers.

The construction which forms the subject matter of my present invention embraces certain advantages of cheapness, and efficiency of operation, and capability of being modified to suit certain special requirements in use, which differentiates it from said patented invention, and for which I desire to secure Letters Patent.

A is a board which may be of plain wood, 70 but for which I prefer to use a special construction of material, as it is essential to the operation of this device that the lower margin of said board and its free edge along the clamping surface should be flat and not 75 warped, or the device will tilt to and fro and interfere with its use in writing upon the papers held therein. For this purpose I use a board built up in layers, and glued together, so that the grain of the wood of the two outer 80 layers, a^4 and a^6 shall run across the grain of the middle layer, a^5 . More than three layers may be used if desired, but three give the best results in my experience. I use this board finished with varnish, or the like, along 85 the edges, but not supported in panels, or doweled to marginal strips, the edges being free, as cut. These boards may have a width of six, eight, or twelve inches, and a length of twelve, fifteen or more, according to the 90 dimensions of the papers to be clamped. I usually round the corners somewhat to avoid scoring the table upon which the device may be used. At or near its raised upper part I pivot one or two bell-crank clamping arms, 95 B B, having a rise, B', nearest the point of impingement upon the board of the clamping jaws, B, to clear the board and give room for the papers, and a downwardly extended portion, B², at the bottom of which is the pivot, 100 B³, by which the said clamp is secured to the pivot support, A', of the board, A. The clamping arm is continued beneath this pivot at an angle, either backwardly, as in Figs. 1, 2 and

3, or forwardly, as in Figs. 4, 5, and 7, extending along beneath the free or raised margin of the board, A, longitudinally, so that, when downward pressure is applied to this 5 raised end of the said board, the free angular ends of the clamping jaw will engage upon a fixed support below, and the said clamping jaw will be rocked upon its pivoted support, A' B³, which will cause the clamp- 10 ing ends of said jaw or jaws, B, to be raised from said board in the arc of a circle, upon B A' as a radius, and form an opening into which papers may be inserted between said clamping jaw and said board. To compress 15 this clamp, and support the raised free end of the supporting board, the spring C is em- 20 ployed. This spring may be of any form de- 25 sired, flat, coiled, or angular, and may be se- 30 cured in various ways, but I prefer to use the 35 construction shown, in which the spring or 40 springs, C, are of flat metal, and secured at 45 one end to the under side of the board, A, so 50 as to allow the free end, extending to the front 55 raised end of and beneath the said board, A, 60 to be vibrated under spring tension. These 65 springs may be attached directly to the free 70 under arms of the clamping jaws, forming 75 their bell-crank extensions, B³ B³, which will 80 thus rest upon the table and form the support 85 for the free raised end of the board, A; but 90 in such case these arms will grind by their ex- 95 tremities upon the table beneath, even if pro- 100 vided with rollers, as they may be, or else will 105 cause slip of the board when it lies upon the 110 table, since the distance from the unsup- 115 ported margin of the board, upon the table, to the pivot, A', and thence to the end of the 120 bell crank arm, is greater than a straight line 125 along the table between the said points. To 130 avoid this I prefer to secure the free ends of the springs, C, C, to a preferably wooden cross 135 bar, E, to the upper surface of which they are 140 attached by screws, s, s, Fig. 7, and I make 145 this bar, E, cylindrical in form, so that as the 150 springs are compressed it will correspond- 155 ingly rotate upon the table and thus avoid the 160 difficulty described. To this bar, E, I secure 165 the bearings or bell-crank attachments which 170 actuate the clamping jaws. In Figs. 1, 2 and 175 3 I use a small link, D, secured at one end to 180 an eye, F', of the plate, F, which secures the 185 spring, C, to the bar, E, which gives a very 190 free movement, while in Figs. 4, 5 and 7 I 195 merely run the bell-crank arm through a 200 sleeve between the plate, F, and the cross bar, 205 E, shown at F², so that the angular-distance 210 is taken up by play on the bar, E, instead of 215 on the table, T. The plate, F, I prefer to ex- 220 tend along the bar, E, the distance between 225 the springs, C C, when I use two springs, 230 which I do not always do in narrow construc- 235 tions, as they thus insure accuracy of spacing, 240 and also afford slide bearings for the bell- 245 crank arms, B³, of the clamping jaw. In the 250 middle portion I form this plate, F, with a 255 loop, F⁸, thus producing a handle by which 260 the whole device may be hung upon a wall, as it

operates quite as well in this position as when 70 horizontal. At F⁴ I also show a central rise in 75 the plate, F, forming a socket into which en- 80 gages, when desired, the bolt, G, see Figs. 4, 5 85 and 7, whereby the device may be held open to 90 remove and file papers away, when the per- 95 forating holder is used instead of a simple com- 100 pression clamp. This bolt I make to work 105 so free in its keeper, G', that by merely turn- 110 ing the device in one way or another, with 115 the spring, C, compressed, it will drop in or 120 out of the recess, F⁴. The forward end of the 125 bolt, G, is bent downward and then forward 130 as shown at G², Fig. 4, to permit it to enter 135 the socket freely, and a small stud, in rear 140 prevents its escape. The small screws, g g, 145 secure the keeper to the under side of the 150 board, A. To secure the rear end of the 155 spring, C, to the board, A, a simple perfora- 160 tion may be used, and a screw, C⁷ C', as shown 165 in Fig. 6^a; but to insure a strong strain I use 170 the device illustrated in detail in Figs. 6 and 175 6^b. When two springs are used, as in Fig. 180 6^b I join the spring holders, C³ C³, by a cross- 185 bar, C⁵, so as to maintain distance, as is done 190 by the corresponding plate, F, at their for- 195 ward end. This bar, C⁵, also assists in 200 strengthening the board, A. A small metal 205 casting open through, at C⁶, and having a 210 raised forward edge, c³, is provided with a 215 pin, C⁴, cast on, and projecting upward to- 220 ward the board, A. Screw holes, C', enable 225 this holder to be secured to the under side of 230 the said board, as shown in Fig. 6. The per- 235 foration, c', at the end of the spring, C, is 240 hooked on to the pin, C⁴, and its forward end 245 is then drawn down, after the screw, C⁷, has 250 been applied, and secured to the bar, E, and 255 the clamp, B, secured to the same holds all 260 in place under strong tension, the spring, C, 265 being strained over the raised edge, c³.

In Figs. 1, 2 and 3 the bell-crank pivot, B⁵, 110 of the clamping arm is at the extreme front 115 of the board, A, and the clamping jaws ex- 120 tend to the rear, which is the margin which 125 rests directly upon the table; but in Figs. 4, 130 5, and 7 the clamping lever is reversed, and 135 is seated in a slot, or slots, A⁴, in the board 140 A. I usually use two of these clamps, as 145 shown in Fig. 7. They are cast flatwise, or 150 otherwise formed, and have pivot supports, 155 B⁵ B⁵, Fig. 7 which rest upon the board, A, 160 alongside the slots, A⁴, and are covered and 165 held down by the rearward extension, B⁵ A', 170 Figs. 4 and 5, grooved transversely for their 175 reception, and thus forming a pivot bearing. 180 The forward free ends of these clamping jaws 185 are separately pointed as shown in Fig. 6, and 190 above these points I prefer to form eyes, B⁶, 195 whereby a cord may be inserted and the per- 200 forated papers drawn off, when the bolt, G, is 205 locked, and tied up in bundles, by means of 210 said cord or string.

To insure perforation, I provide a raised 215 seat, A³, preferably of cast metal, at the for- 220 ward end of A, in which are openings, a³, for 225 the reception of the points, B, as shown, which 230

thus pass down through these perforations, impaling the papers in their descent. A² is a raised part for the fingers to enable the top to be depressed without touching the papers already filed, and the slope, A³, is to enable the papers to be more readily held in place while being filed.

In using this form the papers are inserted, face side down, from beyond the front, and when impaled they are drawn forward around the looped or raised parts, B' B², of the clamping arm, when they will lie flat upon the board A, face side uppermost. I also modify my device in various other ways without departing from the principles of my invention.

Having now described my invention, what I claim, and desire to secure by Letters Patent, is—

1. A device for clamping and holding papers consisting of a flat supporting board, adapted to rest by its rear margin upon a table, its forward margin raised and supported upon a spring support, under tension, and provided with a bell-crank clamping arm pivoted to said board near said front margin, near the middle of said clamping arm, its upper free end forming a clamping jaw, and its lower free end forming an angular support beneath said board, and adapted by the depression of said free forward margin thereof to tilt up, on said pivoted bearing, the upper free end of said clamping jaw from said supporting board, under spring pressure, and when said depression of said board is removed, to cause said clamping jaw to engage under spring pressure upon said board, substantially as described.

2. In combination with a flat board adapted to rest by its rear margin upon a table, a spring adapted to raise and support the free forward end of said board under spring tension, and an angularly shaped clamping device pivoted to said board near its raised front margin, its upper portion forming a spring clamping jaw against said board, and its under portion extended longitudinally along and beneath the line of said board, and downwardly therefrom, substantially as and for the purposes described.

3. In combination with a flat supporting board, one end adapted to rest upon a table, and the opposite end raised therefrom and supported directly or indirectly by a spring, a clamping device having an upper clamping jaw and a lower lever extension, pivoted to said board and under spring tension to close said jaw, said board adapted, when forced downward at its free end, to cause by its movement the said clamping device to rotate upon its pivoted bearing, and release the pressure of said jaw from said board, by the compression of said lever against or toward the under surface of said board, substantially as described.

4. In combination with a board adapted to rest along its rear margin upon a table, and

a spring adapted by its tension to sustain its forward margin raised from said table, a pivoted clamping device secured by a pivot bearing to the said board at or near its free margin, and actuated by the tension of said spring and the depression of said free margin of said board to cause rotation of said clamping device upon said pivot, said clamping device having a clamping point adapted to engage with said board, a raised portion intermediate between said clamping point and said pivot, and a longitudinal arm extended angularly downward from said pivoted bearing and adapted by its leverage to raise and depress, under spring tension the said clamping point, substantially as described.

5. In a paper clamping and holding device, the combination of board, A, supported upon table, T, at one end, and spring, C, at the other, together with angular, pivoted clamping device, B, pivoted to said board at A', and having arm, B³, extended longitudinally downward from said pivot, and connected operatively with said spring C, substantially as described.

6. In a paper clamping and holding device, the combination of supported board A, having marginal contact in rear with a desk or table, spring C, angular bell-crank clamping and operating device, B, having pivot B⁵ and pivot support A' on said board, A, near its free and spring-supported margin, substantially as and for the purposes described.

7. In combination with a paper supporting board, adapted to rest at its rear margin upon a table, and a spring support beneath its forward free margin, adapted to raise the same and maintain it in a permanently raised position, a paper holding clamp pivoted to said board near its free margin, having an upper arm or arms extended forward toward said free margin of said board, in the form of a raised arch, terminating in one or more pointed perforating extremities, and a lower arm extended longitudinally forward along and beneath said board, in operative connection with said spring support, together with one or more recesses for the reception of said perforating points, substantially as and for the purposes described.

8. In a device for clamping and holding papers the combination of board, A, spring C, angular clamp, B, having arm B' B², pivoted to A, at A' B⁵, and lower angular arm, B³, and cross bar, E, said bar, E, in operative connection with said spring, C, and said angular arm, B³, substantially as described.

9. In combination with board, A, spring C, cross bar E, and angular clamping arm, B, having integrally attached longitudinal operating arm, B³, the guide plate, F, having guide grooves, F², substantially as described.

10. In combination with a spring actuated perforating and holding jaw, and a supporting board, and supporting cross-bar beneath said board adapted to form a yielding sup-

port, for said spring and said jaw, a locking bolt secured to the under side of said board, and above said cross-bar and spring, and adapted to engage with the board-supporting cross-bar which rests upon the table, and is constructed to support the free end of said board under spring tension, and lock the said jaw open against spring pressure and permit the removal of papers from said perforating

10 and holding jaw, substantially as described.

11. In combination with a board A, spring C, and spring actuated clamping jaw operatively connected therewith, a spring support for said spring consisting of projecting edge, 15 c^3 , recessed support, C^6 , pin C^4 , and rearward lug having screw support, C' , said pin adapted to engage in a terminal perforation, c' , in said spring, and said spring adapted to be held under strain against said edge, c^3 , substantially as described.

12. In a device for clamping and holding papers, in combination with board, A, springs C, C, and clamping jaw, B, the spring holders, C^6 C^6 , said springs having independent operative attachments to the said board, said 25 spring supports joined by the connecting bar,

C^5 , permanently formed therewith, substantially as and for the purposes described.

13. In a device for clamping and holding papers the combination of board, A, springs, 30 C, C, and clamping jaw, B, with the transverse bar, E, said springs connected under tension at their rear ends with the undersurface of said board, A, and at their forward ends with said bar, E, and said clamping jaw 35 in operative connection with the same, said bar E consisting of a cylindrical rod of wood, substantially as described.

14. In combination with board, A, spring, C, clamping jaw, B, having raised upper portion, B' B^2 , and longitudinal downward arm, B^3 , the cross bar E, and covering plate, F, said plate adapted to form screw-hole supports, for screws s s , through perforated springs, C, C, and into wooden cross bar E, and sleeves, F^2 45 F^3 , for passage of angular arms, B^3 B^3 , of said clamping jaw, substantially as described.
